Specification for Design.

Patented Nov. 22, 1921.

Application filed May 17, 1921. Serial No. 470,479. Term of patent 7 years.

To all whom it may concern:

Be it known that I, WALTER F. HEROLD, a citizen of the United States, residing at Newark, in the county of Essex and State of New Jersey, have invented a certain new, original, and ornamental Design for a Caster-Wheel, of which the following is a specification, reference being had to the accompanying drawing, forming part thereof.

In the drawing Figure 1 is a perspective view of a caster wheel, showing my new design, as viewed from one side, and Fig. 2 is a side elevation of the caster wheel as viewed from the opposite side.

I claim—

The ornamental design for a caster wheel as shown.

WALTER F. HEROLD.
